US0D1009931S

(12) **United States Design Patent** (10) **Patent No.:** **US D1,009,931 S**
(45) **Date of Patent:** **** Jan. 2, 2024**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Gary Butcher**, Los Gatos, CA (US);
Kevin Will Chen, Cupertino, CA (US);
Alan C. Dye, San Francisco, CA (US);
Jonathan P. Ive, San Francisco, CA (US);
Brian Andrew Schmitt, San Francisco, CA (US)

(73) Assignee: **Apple Inc.**, Cupertino, CA (US)

(**) Term: **15 Years**

(21) Appl. No.: **29/847,414**

(22) Filed: **Jul. 25, 2022**

Related U.S. Application Data

(63) Continuation of application No. 29/808,712, filed on Sep. 22, 2021, now Pat. No. Des. 958,813, which is a continuation of application No. 29/694,382, filed on Jun. 10, 2019, now abandoned, which is a continuation of application No. 29/618,012, filed on Sep. 18, 2017, now abandoned, which is a continuation of application No. 29/583,594, filed on Nov. 7, 2016, now Pat. No. Des. 797,784, which is a

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The dashed broken lines in the FIGURE show a display screen or portion thereof, and form no part of the claimed design. The dot-dash broken line in the FIGURE and the area within the dot-dash broken line show a portion of the graphical user interface that forms no part of the claimed design.

1 Claim, 1 Drawing Sheet

Related U.S. Application Data

continuation of application No. 29/557,331, filed on Mar. 8, 2016, now Pat. No. Des. 771,076, which is a continuation of application No. 29/501,092, filed on Sep. 1, 2014, now Pat. No. Des. 752,624.
